UNITED STATES PATENT OFFICE.

WILLIAM RANSLEY, OF EAST ORANGE, NEW JERSEY.

METHOD OF FILING SLOTS IN ARMATURES, STATORS, AND THE LIKE.

1,322,615.

Specification of Letters Patent. Patented Nov. 25, 1919.

Application filed December 6, 1918. Serial No. 265,521.

To all whom it may concern:

Be it known that I, WILLIAM RANSLEY, a citizen of the United States, and a resident of East Orange, county of Essex, and State 5 of New Jersey, have invented certain new and useful Improvements in Methods of Filing Slots in Armatures, Stators, and the like, of which the following is a specification.

10 My invention relates to an improved method of filing slots in elements of electrical apparatus such as armatures, stators, etc.

In the construction of such elements, cores therefor are made from a number of substantially identical punchings made from sheet metal coated with insulating material and assembled together, providing slots extending lengthwise through the members so made up and serving for the reception of 15 coils, bridge plates and the like.

These slots must be dressed and trued up after assembly, and this work is now done, so far as I am aware, with long files passed lengthwise into the slots from the ends thereof.

20 To do the work in this manner is tedious and expensive and skilled workmen are required to perform the operations with the necessary accuracy, which is not always to be secured even with highly skilled and paid 25 operators.

According to the present invention this work is performed by rotating files extending into the slots from the open sides thereof, operated by power and guided lengthwise of the slots in any suitable way as the same are moved in a straight line direction relative to one another, producing slots with smooth, accurate surfaces on their inner walls and bottom, which work may be performed with rapidity and accuracy and in a 30 highly economical manner as compared with former practice.

In the accompanying drawing, forming part of this specification, I have illustrated 35 the steps of the process and tools for carrying the process into effect.

In said drawing, Figure 1 is a cross-sectional view of a portion of a stator member with a file for filing out bridge plate grooves. 40 Fig. 2 is a similar view showing a file for filing out the sides and bottom of the slot. Fig. 3 is a perspective view of the file shown in Fig. 2. Fig. 4 is a view similar to Fig. 2 and illustrating the filing of a slot in an 45 armature member and without bridge plate

grooves. Figs. 5 and 6 are front views of modified forms of files for filing bridge plate grooves, and Fig. 7 is a bottom view of the file shown in Fig. 6.

The files shown at 10, 11 and 12, Figs. 1, 5, 6 and 7, are formed for filing grooves for bridge plates of various forms and having laterally projecting file portions 10^a, 11^a and 12^a adapted to fit such grooves of different forms. The files 10, 11 and 12 are preferably 60 formed with extensions 10^b, 11^b and 12^b extending beyond the laterally projecting file portions 10^a, 11^a and 12^a, and such projecting portions may serve effectively as a means for conducting away excess heat and preventing the filing portions proper from getting unduly hot, but the provision of such extensions may be dispensed with, if desired. A file such as shown at 13, having a cylindrical filing surface 13^a and having a 65 square ended portion 13^b provided with a filing surface, serves for filing the sides and bottoms of slots provided for the reception of coils and the like.

70 The files are rotated in use by power supplied, for example, by means of a chuck 14 adapted for receiving the shanks 15 of the rotary files, and are guided in straight line movement relative to the core being operated upon in any convenient manner. In 75 filing a straight-sided slot such as shown at 16, Fig. 4, and which may be used, for example, in an armature core, the file 13 is used to file the side and bottom walls of the slot, being preferably first guided in straight 80 line movement relative to the core and in contact with one side and a portion of the bottom of the slot, and after same has been filed smooth the file is brought into contact with the remaining side of the slot and 85 moved relatively thereto in straight line movement, thereby completing the filing of the second wall and the remainder of the 90 bottom of the slot.

95 In filing slots having grooves 19 in their 100 sides for the reception of bridge plates and the like, the bridge plate grooves are preferably first filed smooth, the form of file used varying with the form of the bridge plate groove, the file 10, as shown in Fig. 1, 105 being adapted for the filing of grooves of the form shown in such figure, and the files shown in Figs. 5 and 6 being adapted for use with grooves of forms corresponding to the 110 projecting file portions 10^a, 11^a and 12^a.

Where bridge plate grooves of other forms are used, files constructed to fit therein may, of course, be provided. The filing of the bridge plate grooves is accomplished in the same manner as already described, the file being rotated while it is guided relatively to the work in straight line movement so as to produce a smooth and accurate surface. The bridge plate grooves are preferably filed first, the tool being guided first into contact with the groove on one side of the slot and then into contact with the groove on the other side. In filing up the bridge plate grooves more or less burs, as indicated, for example, at 17, Fig. 2, are usually formed on each side of the groove, and after the bridge plate grooves have been filed out the filing of the walls and bottom of the groove, including the removal of such burs, if formed, is completed, as indicated in Fig. 2, in the same manner as already described with respect to Fig. 4. The straight line movement referred to, it will be understood, takes place at right angles to the plane on which the cross-sectional views of the drawing are taken.

It will be seen that the rotary files made use of extend into the grooves through their open sides, as indicated, for example, at 18, Fig. 4, as distinguished from the ends of grooves, and that by the process of the present invention slots may be filed straight and smooth with a minimum of expense, time and trouble, and that highly accurate work can be readily turned out in large quantities,

thereby greatly facilitating the manufacture of devices of the character referred to.

I claim:

1. The process of making slotted electrical units, such as armatures, stators and the like, which consists in providing a plurality of slotted plates, assembling same to make up a unit with slots therein, introducing a rotary tool into such slot with its shank projecting from the open side thereof, guiding such tool in straight line movement relative to the walls of the slot, and rotating such tool in contact therewith.

2. The process of filing slots formed in cores of electrical apparatus and having bridge plate grooves in their sides which consists in effecting relatively straight line movement between a slotted core and a rotatable file extending into the slot from the open side thereof and having a file toothed extension fitting into the bridge plate groove, rotating such file in contact with the walls of the groove, whereby the groove walls are finished, and thereafter effecting relative movement between such core and a file having substantially cylindrical file toothed sides and a file toothed end, and rotating such file in contact with the sides and bottom of the groove whereby same are finished smooth.

In testimony that I claim the foregoing, I have hereto set my hand, this 5th day of December, 1918.

WILLIAM RANSLEY.
